ABRADING TOOL

Lawrence O. Beard, Lancaster, Pa.

Application August 8, 1938, Serial No. 223,774

3 Claims. (Cl. 51—184.3)

My invention relates to an abrading tool adapted for truing or honing hydraulic brake cylinders and the like.

The principal object of the invention is to provide an abrading tool adaptable for insertion in a brake cylinder and wherein means is provided to assure an efficient cutting action at the lower end of the cylinder.

Another object is the provision of a tool having means for increasing the parallel expansion of the abrading members.

Another object is to provide abrading members having readily removable and replaceable abrasive means secured thereto.

These and other objects and advantages will be apparent as the specification is considered with the accompanying drawing, in which:

Figure 1 is a side elevation of a tool embodying the invention;

Figure 2 is an enlarged view of the tool shown in Figure 1;

Figure 3 is a section on the line 3—3 of Figure 2;

Figure 4 is a perspective view of one of the abrading members;

Figure 5 is an enlarged perspective view of the retaining screw; and

Figure 6 is a cross section of a modified form of abrading member seated in a modified form of slot in the shank on the tool.

Referring more particularly to the drawing, wherein like reference characters designate like parts throughout the several views, numeral 1 represents the shank of the abrading tool, which is formed with the smooth unthreaded portion 2 and top threaded portion 3. The shank 1 is also provided with V-shaped longitudinal slots 4, of graduated depth, the upper or inner ends 5 of the slots being inclined relative to the axis of the shank, and the side walls 6 converging with each other.

Abrading members 7, V-shaped in cross section and of graduated depth and thickness, movably inserted in said slots, are provided with tapered end faces 8 and 9 engaged with the beveled end 11 of a collar 12, in turn held in place by a confining nut 13 screwed upon the threaded portion 3 of the shank, and the beveled face 15 of a knurled retaining screw 14 which is threadedly received in a bore 16 in the lower end of the shank.

V-shaped metal shims or backing plates 17, of graduated depth, are inserted in the slots 4 and dents or raised portions 18 are formed thereon, which dents are adapted to fit into notches or

recesses 20 in the rear edges 19 of the abrading members 7, when the latter are positioned in the slots and rest on the shims. Thus it will be seen that the shims increase the diameter of the tool and permit the abrading members to be expanded further as hereinafter described. The notches and dents retain the shims in position with respect to the abrading members and prevent the shims from sliding or slipping.

The abrading members and shims are assembled by sliding them along the slots 4 until the tapered ends 8 and 9 engage the beveled faces of the collar 12 and retaining screw 14, and then screwing up the nut 13 to cause the collar 12 to engage the tapered ends 8, thus clamping the members 7 tightly in place. Parallel expansion of the abrading members 7 is accomplished by loosening the retaining screw 14 and screwing up the nut 13, in a manner readily understood.

In some instances, in order to obtain a greater range of expansion, two sets of relatively narrow slots or grooves 4' and 4'', of uniform width but of varying depth, are formed in the shank and into which relatively narrow fins or tongues 30 formed on the abrading members 7' are adapted to fit, as shown in Figure 6. Thus, the alternately positioned slots 4' are relatively deep and the alternately positioned slots 4'' are somewhat shallow or of a lesser depth, whereby the abrading members 7' give a smaller diameter when placed in the deepest set of slots 4' and are caused to provide a larger diameter when removed from slots 4' and arranged in the shallow set of slots 4''. When using this form of abrading member it is unnecessary to provide shims or backing plates, which is sometimes desirable as it reduces the number of parts.

Thin, flexible, metal shells or backing sheets 21, of tin or the like, are adapted to snugly fit the curved working faces 22 of the abrading members 7, and the side edges 23 thereof are bent rearwardly and inwardly and extend into grooves or slots 24 in the sides of the members 7. Thin sheets of emery cloth or other suitable abrasive material 25 are positioned on and clamped to the shells 21 by the crimped or rolled edges 26 of the shells whereby the abrasive and shells are caused to conform closely to the contour of the abrading members. In addition to providing a purchase for the bent edges of the abrasive sheets, it will be noted that the grooves or slots 24, in the sides of the members 7, increase the thickness and depth thereof. This is desirable in that it renders the same more stable and substantial. A flange or rib 27 is

preferably formed at the upper end of each abrading member for holding the abrasive sheet in position and preventing the same from slipping or sliding off the abrading members during the grinding operation.

By virtue of the relative narrow head 28 and relatively flat bottom face 29 of the retaining screw 14, it will be readily understood that the lower ends of the abrading members 7 are only slightly spaced from the lower end of the tool. Therefore when the tool is inserted and rotated in a brake cylinder, not shown, the possibility of a burr or ridge being left at the bottom of the cylinder wall is greatly minimized.

It will of course be understood that when the abrasive sheets 25 become worn or otherwise damaged, the same may be readily removed from their metal backing sheets 21 by simply straightening out the bent or crimped edges 26 of the latter, or if necessary, both abrasive and backing may be removed and replaced as a unit.

While better results are obtained by employing the metal shims the same may be eliminated if so desired. It is also to be understood that various changes and modifications may be made in the preferred form of tool illustrated in the drawing, without departing from the scope and spirit of the appended claims.

Having thus described my invention what I claim is:

1. An abrading tool for brake cylinders and the like comprising a shank having elongated slots of graduated depth therein, elongated abrading members of graduated depth fitting within said slots, abrading means removably superposed on said members, and means on said abrading means engageable with means on said abrading members for holding said abrading means thereon, removable means in said slots for supporting and ex-

panding said abrading members, and a relatively narrow beveled retaining screw means in the end of said shank for clamping said abrading members in position on the shank.

2. An abrading tool for brake cylinders and the like comprising a shank having elongated V-shaped slots of graduated depth therein, elongated V-shaped abrading members of graduated depth fitting within said slots, abrading elements removably superposed on said members, the edges of said elements being bent and adapted to fit into grooves in said abrading members whereby said elements are clamped in position thereon, V-shaped means in said slots for supporting and increasing the expansion of said abrading members, and a relatively narrow beveled screw threaded means in the end of said shank for clamping said abrading members in position on the shank.

3. An abrading tool of the character described comprising a shank having elongated V-shaped slots of graduated depth therein, elongated V-shaped abrading members of graduated depth fitting within said slots, abrading elements removably superposed on said members, the edges of said elements being bent and adapted to fit into grooves in said abrading members whereby said elements are clamped in position thereon, V-shaped means in said slots for supporting and increasing the expansion of said abrading members, and means on said V-shaped means cooperating with means in said abrading members for retaining said V-shaped means in position with respect to said members, and a relatively narrow beveled screw threaded means in the end of said shank for clamping said abrading members in position on said shank.
